UNITED STATES PATENT OFFICE.

OSCAR A. SHIPLEY, OF RAHWAY, NEW JERSEY.

TRUSS.

1,179,766.

Specification of Letters Patent. Patented Apr. 18, 1916.

Application filed December 30, 1915. Serial No. 69,372.

To all whom it may concern:

Be it known that I, OSCAR A. SHIPLEY, a citizen of the United States, and a resident of Rahway, county of Union, and State of New Jersey, have invented certain new and useful Improvements in Trusses, of which the following is a specification.

This invention relates to an improved supporter or truss and is particularly adapted for use for supporting the abdomen, and is specifically designed for ruptures and the like, the truss being comfortable, and while resilient enough to conform freely to the movements of the body, it gives the person wearing the same a feeling of security and comfort. The truss is of the type that is supported on the back and is made to conform substantially to the shape of the body without, however, touching the body except at points where the support is to be located, so that the sides of the body are left comparatively free.

The invention relates further to a truss of this kind which is adjustable to an extent in which any lack of resiliency or change of shape, due to constant wear, can be taken up, and in which the parts that hold the truss on the body, and from which it is supported, are tiltable or can be rocked on the body portion of the truss.

The invention is illustrated in the accompanying drawing, in which—

Figure 1 is a top view of a truss made according to my invention. Fig. 2 is a front view of the truss shown in Fig. 1. Fig. 3 is a section on line 3—3, in Fig. 1, and Fig. 4 is a section on line 4—4, in Fig. 1, with a portion of the elements shown in such section illustrated in elevation to more clearly illustrate their form.

The truss has a main or body portion which is made of resilient material, preferably spring steel which is in the form of wire, this body portion 10 having the curved portions 11 at each side and extending across the front in a manner to conveniently adapt it for the adjustable securing of pads for pressure on the parts to be supported.

The type shown illustrates a support comprising the central portion 12 of the wire which is connected with the side portions 11 and is usually raised therefrom by the

bends 13 so that a substantially arch-shaped structure is formed with a bracing strand 14 extending from the upright parts 13 and 55 being suitably secured thereto, the bracing strand being substantially parallel to the central portion or strand 12. Clips 15 are arranged so that they extend around the central strand 12 and the bracing strand 14, 60 these clips being provided in the required number, usually one or two, the clips acting to support the pads, one manner of supporting the pads comprising studs or screws 16 which pass through the perforations 17 in 65 the narrow or compressed part of the clips 15, the studs 16 having any desired form of supporting pad 18 attached thereto, and being held in place by fastening means such as the nuts 19 and 20. When the nuts 19 70 and 20 are screwed up tight to fasten the stud in place, they also act to compress the side walls 21 of the clips and fasten the clips against sliding movement along the two front strands 12 and 14 of the body portion. 75 The clips are usually made resilient enough to spread apart slightly when the nuts 19 and 20 are unscrewed so that they can be slid to any desired position according to the exact location where the pad 18 is to 80 be desired by the wearer.

The side strands or portions 11 are curved with their extremities adapted to hold means that will bear against the back portion of the body, preferably in the neighborhood of 85 the lower part of the spine and so act to support the truss from this part of the body. Two supporting plates or disks are preferably provided, one on each side, separated sufficiently to give comfort by not being 90 close enough to the spine to press thereon in any way, and each of these supporting pads 22 is usually made of a disk 23 having a post 24 thereon, the disk 23 having a covering 25 of any suitable material such as hard rubber or the like which will protect the metal and also the body by preventing any corrosion of the metal by the acids or other elements on the body which would come in contact with the metal, and in turn preventing 95 the body from any ill effects from the metal, rubber also providing a good surface for cleanliness, since it is easily kept clean, but it will be understood that material other 100

than hard rubber can be used if found desirable.

Each post 24 has an opening 26 therein, each opening acting to receive an end 27 of a curved strand 11 of the body portion, these ends 27 being provided with notches 28 of a desired number and suitably placed. Each post 24 is provided with a hole 29 through which a cotter pin 30 is passed, the cotter pin being adapted to be passed through one of the notches 28, the notch being large enough to permit some play to the cotter pin so that the supporting plate can be tilted to an appreciable extent on the end 27 of the body portion, but it cannot move longitudinally. Other fastening means besides a cotter pin can be used, but a cotter pin is the desirable fixture for this kind of fastening means, as it is easily removed by hand without the use of any tools, the cotter pin being made of comparatively soft material and being easily bent by the fingers. Each post 24 has a stud 31 thereon, the studs being headed as at 32. A substantially flexible strap 33 is provided with button-holes 34 that are buttoned over the studs 31 and are held in place by the heads 32 and connect the posts 24, and in this way also act to connect the ends 27 of the body portion.

The strap 33 can be of ordinary material, such as canvas or leather, but I prefer to make it so that it will not stretch to any material extent, this being accomplished by covering a strip of material 35, such as sheet metal, with canvas or leather so that the strap will not stretch to any appreciable extent. The strap as a connection acts to permit one of the supporting disks and its post to tilt on the body portion without affecting the movement of the other stud, and it gives a degree of flexibility to the structure that permits the truss to adapt itself quickly to any change of position or movement of the body either on one or both sides. This independent tilting of the supporting plates provides a smooth, even support for the truss, even when the wearer is walking. The notches and the cotter pin provide a quick and convenient means for varying the size of the truss, the truss being usually worn so that the supporting plates 22 and the pads 18 are the only portions thereof that contact with the body, the end portions 11 being usually disposed so that they extend slightly beyond the body and do not come in contact therewith, being of a larger radius than the size of the body at the point at which they are worn, and thus giving the patient freedom of movement at the intermediate points, but giving a positive and comfortable pressure and support where it is needed. The pads and the supporting plates can be shifted by the person wearing the truss to the most advantageous and comfortable position, and the structure

is calculated to be used with any desired number of pads, the illustration, however, showing two pads in position.

Each supporting plate is preferably made so that it has no parts that can be separated, the disk and the post and the headed stud being made in one piece so that there is no opportunity for any of the parts to work loose, which is a defect with such types of trusses as have small screws and other similar parts that eventually work loose, due to vibration and the working of the body while the truss is being worn. The metal disk 23 is of substantial area, and while I have defined rubber as covering it, it will be understood that any non-corrosive material can be employed for this purpose. The strap 33 is not primarily designed for any adjustment, but is adapted to connect the bosses or posts of the supporting plates, the adjustment for the different sizes of truss being made by withdrawing the cotter pin from a notch and putting it in some other desired notch.

Having thus described my invention, I claim:

1. A truss comprising a resilient body portion curved at the sides, a flexible connection at the back thereof, the body portion being formed into a substantially flat top arched at the front, a bracing strand extending across the arch, a spring clip engaging the arch and the bracing strand and slidably thereon, a pad, and means for fastening the pad to the clip, said fastening means acting to clamp the clip so that it cannot slide.

2. A truss comprising a resilient body portion curved at the sides, a flexible connection at the back thereof, the body portion being formed into a substantially flat top arched at the front, a bracing strand extending across the arch, a clip of spring material embracing the top strand of the arch and the bracing strand and slidably thereon, the connecting walls of the clip being perforated, a stud passing through the perforation, means on the stud for fastening the stud in the perforation and forcing the walls together so that the clip is pressed so that it cannot slide, and a pad on the stud.

3. A truss comprising a body portion of spring metal having free ends at the back, the free ends having notches therein, posts slidable on said free ends, pins passing through the posts and adapted to be placed in the notches and fitting freely enough in said notches to permit a limited tilting of the posts, supporting plates on the posts, headed studs on the back of the posts, and a flexible bendable connection between the studs on the posts.

4. A truss comprising a body portion of spring metal having free ends at the back,

the free ends having notches therein, posts
slidable on said free ends, pins passing
through the posts and adapted to be placed
in the notches and fitting freely enough in
5 said notches to permit a limited tilting of
the posts, supporting plates on the posts,
headed studs on the back of the posts, and
a non-elastic flexible connection having

holes therein to receive the headed studs
on the posts, said connection permitting 10
tilting of said supporting posts relative to
each other.

In testimony that I claim the foregoing,
I hereto set my hand, this 28th day of
December, 1915.

OSCAR A. SHIPLEY.
